UNITED STATES PATENT OFFICE.

GUSTAV PAGEL, OF CHARLOTTENBURG, GERMANY, ASSIGNOR TO GENERAL ELECTRIC COMPANY, A CORPORATION OF NEW YORK.

CENTRIFUGAL AIR-PUMP.

1,089,665.

Specification of Letters Patent. Patented Mar. 10, 1914.

Application filed May 10, 1911. Serial No. 626,240.

To all whom it may concern:

Be it known that I, GUSTAV PAGEL, a subject of the King of Prussia, residing at Charlottenburg, Germany, have invented 5 certain new and useful Improvements in Centrifugal Air-Pumps, of which the following is a specification.

Apparatus for removing vapors and uncondensed gases from condensers must, if 10 the vacuum in the condenser is to be kept constantly as high as possible, be regulable within rather wide limits since it often happens that the steam engines or turbines with which the condenser is used are subjected to relatively great changes in 15 operating conditions. In reciprocating or piston air pumps the necessary regulation can be obtained by varying the number of strokes or revolutions but the regulation of 20 throwing-water air pumps, by a change of the speed of rotation is often not applicable or not sufficient, and the object of the present invention is the provision of means for effectively regulating such pumps by reducing the supply of throwing-water without impairing the efficiency of the pump due 25 to the throttling of the supply and the consequent loss of head which is objectionable in all cases where complete utilization of 30 this head is essential to the efficient operation of the pump. Said loss is obviated by the invention and although the quantity of the throwing medium is varied, the head of 35 the latter existing at any time remains unchanged. This result is obtained by arranging an adjustable regulating member just in advance of, or at only a small distance from a place where the pressure or velocity 40 of the auxiliary medium undergoes a change due to the action of any means. If the regulating member is in the form of a valve, it may also serve as a supplying device for the auxiliary medium, thus avoiding impact and eddies when the position of said member 45 is changed.

In the accompanying drawing Figure 1 shows an illustrative construction or embodiment of the invention in a rotary air-suction device working with an auxiliary or 50 throwing liquid medium, preferably water and Fig. 2 is a cross section of the lower portion thereof.

The invention consists of a positively driven impeller wheel 1 mounted on a suitable shaft and a directing ring or member 2

surrounding the impeller. The throwing-water or other auxiliary medium passes through the pipe 3 into the impeller 1 and by reason of the velocity imparted to it by the impeller and its subdivision into separate water-pistons in passing from the impeller to the directing ring 2, it draws into the gap 4 the gases or vapors that enter the pump through the opening 5. The water-pistons force the air, gases and vapor outwardly through the passages of the directing member into the chamber 6, the air, etc., passing off through the conduit 7 and the water through the conduit 8.

The quantity of throwing-water for a 70 given number of revolutions of the pump is regulated by an annular slide valve 9 surrounding the shaft and movable longitudinally thereof, which also serves as a guide or means for directing the throwing-water 75 to the inlets of the passages in the impeller. The valve can be shifted directly in front of said inlets and parallel to the surfaces connecting the bases of the impeller vanes. When the regulating device 9 is shifted by 80 means of the lever 10 and the hand wheel 11, no throttling occurs but only a reduction of the quantity of throwing-water which flows into the impeller 1 so that notwithstanding this regulation the maximum pressure difference which exists between the entrance and exit openings of the impeller can always be completely utilized, a feature which is of great importance to the efficient operation of the pump. This regulation 85 may, of course, be employed with other rotary or fixed air-suction devices and may in some cases be only partial. The shifting of the regulating member may be accomplished automatically instead of by hand, 90 as, for example, by connection with a suitable regulator.

In accordance with the provisions of the patent statutes, I have described the principle of operation of my invention, together 100 with the apparatus which I now consider to represent the best embodiment thereof; but I desire to have it understood that the apparatus shown is only illustrative, and that the invention can be carried out by other 105 means.

What I claim as new and desire to secure by Letters Patent of the United States, is,—

1. The method of regulating an apparatus utilizing an auxiliary liquid medium for 110

- 2 drawing off gases, vapors, and the like by direct action of said medium thereon, which consists in varying the quantity of the auxiliary medium by means of a regulating member that is caused to act on said medium directly in advance of or at a small distance from a place where the pressure or velocity of the auxiliary medium undergoes a change.
2. In an apparatus utilizing an auxiliary liquid medium for drawing off gases, vapor, and the like by direct action of said medium thereon, the combination of means for changing the pressure or velocity of the auxiliary medium as it passes through said apparatus, and a device located at a point closely adjacent the place where said means produces said change which varies the quantity of the auxiliary medium to regulate the operation of the apparatus.
3. In a centrifugal air pump, the combination of an impeller having passages for a throwing medium, means for supplying the throwing medium to the impeller including a regulating member adjacent to the inlets of said passages which varies the quantity of throwing medium supplied to the impeller, means conveying air, to the pump, and a directing member surrounding the impeller through which the throwing medium and the air pass.
4. In a centrifugal air pump, the combination of an impeller having passages for throwing-water, means for supplying throwing-water to the impeller including a valve having passages to direct the throwing-water to the inlets of said impeller passages, mechanism for adjusting the valve to vary the quantity of water delivered to said inlets, and a directing member surrounding the impeller through which the throwing-water and air pass.
5. In a centrifugal air pump, the combination of an impeller having passages for throwing-water, a shaft on which the impeller is mounted, means for supplying throwing-water to the impeller including a valve
- surrounding the shaft and movable longitudinally thereof, mechanism for adjusting the valve to vary the quantity of throwing-water delivered to the impeller, and a directing member surrounding the impeller through which the throwing-water and air pass.
6. In a centrifugal air pump, the combination of an impeller having passages for throwing-water, a shaft on which the impeller is mounted, a valve for regulating the supply of throwing-water which surrounds the shaft and is movable longitudinally thereof, said valve being provided with passages which direct the throwing-water to the inlets of said impeller passages, means for adjusting the valve longitudinally of the shaft to vary the quantity of throwing-water delivered to the impeller, and a directing member surrounding the impeller through which the throwing-water and air pass.
7. In a centrifugal air pump, the combination of a shaft, an impeller on the shaft having a ring provided with passages for throwing-water, a valve for regulating the supply of throwing-water which surrounds the shaft, is movable longitudinally thereof and has a portion arranged within the ring, said valve having passages that convey throwing-water and deliver it from said portion to the inlets of the passages in the impeller, means for moving the valve longitudinally of the shaft to vary the quantity of throwing-water delivered to the impeller without throttling the supply, and a directing member surrounding the impeller through which the throwing-water and air pass.
- In witness whereof, I have hereunto set my hand this day of April 15, 1911.

GUSTAV PAGEL.
